US00D759230S

(12) **United States Design Patent**
Gordon et al.

(10) **Patent No.:** US D759,230 S
(45) **Date of Patent:** ** Jun. 14, 2016

(54) **AIRFLOW GENERATOR FOR A SLEEP APNEA SYSTEM**

(57) **CLAIM**

The ornamental design for an airflow generator for a sleep apnea system, as shown and described herein.

DESCRIPTION

FIG. 1 is a perspective view of an airflow generator for a sleep apnea system showing our new design;
FIG. 2 is a front elevation view thereof;
FIG. 3 is a rear elevation view thereof;
FIG. 4 is a left-side elevation view thereof;
FIG. 5 is a right-side elevation view thereof;
FIG. 6 is a top plan view thereof;
FIG. 7 is a bottom plan view thereof;
FIG. 8 is a partial exploded front view thereof; and,
FIG. 9 is a partial exploded rear view thereof.

1 Claim, 7 Drawing Sheets
